(57) **CLAIM**

The ornamental design for a wheel, as shown and described.

DESCRIPTION

FIG. 1 is an elevational view of a wheel showing one embodiment of my new design;

FIG. 2 is a perspective view thereof;

FIG. 3 is a cross-sectional view taken through line 3—3 in FIG. 1.

FIG. 4 is an elevational view of a portion of a wheel showing a second embodiment of my new design; and,

FIG. 5 is a perspective view of the portion of a wheel of FIG. 4.

In FIGS. 1–3, the non-illustrated opposite side of the wheel forms no part of the claimed design. In FIGS. 4–5, any remaining portion of the wheel not illustrated forms no part of the claimed design. Additionally, the broken line showing of the central hub element in FIGS. 1–5 is for illustrative purposes only and also forms no part of the claimed design.
